UNITED STATES PATENT OFFICE.

ERNEST R. FRIED, OF DETROIT, MICHIGAN, ASSIGNOR TO GENERAL MOTORS COMPANY, OF DETROIT, MICHIGAN, A CORPORATION OF NEW JERSEY.

EXPLOSION-ENGINE.

1,147,855.

Specification of Letters Patent. Patented July 27, 1915.

Application filed June 8, 1912. Serial No. 702,477.

To all whom it may concern:

Be it known that I, ERNEST R. FRIED, a subject of the Emperor of Austria-Hungary, residing at Detroit, in the county of Wayne 5 and State of Michigan, have invented certain new and useful Improvements in Explosion-Engines, of which the following is a specification, reference being had therein to the accompanying drawings.

10 The invention relates to control mechanisms for explosion engines and has for its object the independent and proportionate variation of the air and fuel for each explosive charge. The construction is particularly designed for use in connection with a multi-cylinder engine and one in which each cylinder is provided with a corresponding pump for supplying it with the explosive charge, being adapted for either two or four 15 cycle.

In the drawings, Figure 1 is a diagrammatic view showing a multi-cylinder engine with my control device applied thereto; Fig. 2 is a cross section through the air controlling valve; and Fig. 3 is a diagrammatic view of the connections.

A are the power cylinders of a multi-cylinder engine and which in the construction shown are provided each with an enlargement B forming a pump cylinder, C are the pistons provided with portions for fitting the power and pump cylinders, D, D' and D² are connections between each of the pump cylinders and the inlet port E of another cylinder and F is a rotary valve controlling the admission of air to each of the pump cylinders through the conduits A', A² and A³. The arrangement as thus far described is such that a volume of air admitted to one of the pump cylinders will be transferred therefrom through the connecting conduit to the corresponding power cylinder, the admission being timed by the movement of the piston in uncovering the port E. Instead of handling carbureted air by the pumps, air alone is preferably used and the charge is carbureted at the point of introduction to the power cylinder by the injection of a suitable quantity of liquid 40 fuel.

50 My control mechanism comprises in combination with the construction above described, means for varying the volume of air admitted to each of the pumps and coöperating means

for proportionately varying the quantity of 55 liquid fuel. Thus the proper mixture for explosion is maintained but the quantity is varied according to the requirements of the work.

In detail, the rotary valve F is preferably 60 hollow and receives its air through ports in the end. There are also ports G for registering with the ports H in the valve case connecting respectively with the pump cylinders B, the timing being effected by the 65 positioning of said ports G.

I is an adjustable sleeve preferably arranged intermediate the valve F and its case and which by a rotative adjustment will 70 vary the point of cut-off of the rotary valve, thereby changing the quantity of air drawn 75 into the pump cylinder and subsequently transferred to the power cylinder.

J is a pump for the liquid fuel which delivers the same through a conduit K to a 75 nozzle in the air conduit adjacent the point of entrance to the power cylinder. This pump is provided with means for varying its stroke such as a sliding fulcrum L intermediate two levers M and N which impart movement from a cam O to the pump plunger P.

Q is a link connected to the fulcrum member L, and R is a link connected to a rock arm S on the sleeve I of the rotary valve, 85 said links R and Q being connected to a common actuating crank T.

In operation the crank T may be adjusted to correspondingly adjust the rotative sleeve I and the stroke of the pump J, which in 90 turn will vary the quantity of air and the quantity of liquid fuel introduced into the power cylinder, proportionately. This will control the power of the engine and without danger of stopping the same through improper explosive mixture.

What I claim as my invention is:

1. In a multi-cylinder explosion engine, the combination with a plurality of cylinders and a pump corresponding to each cylinder, of valveless conduits connecting each pump with its corresponding cylinder, a single valve for controlling the admission of air to all the pumps, and means for injecting a measured quantity of liquid fuel 105 into the path of the air passing through said valveless conduit into the cylinder.

2. In a multi-cylinder explosion engine,

the combination with a plurality of power cylinders each having an alined pump cylinder, of valveless conduits connecting each pump cylinder with an unalined power cylinder, a valve controlling the admission of air to the respective pump cylinders, means for injecting a measured quantity of liquid fuel into the path of air passing through each valveless conduit, and means for proportionately varying the quantity of air admitted to said pump cylinder and the quantity of liquid fuel injected.

3. In a multi-cylinder explosion engine, the combination with a plurality of power cylinders, each having an alined pump cylinder, a rotary valve having an air inlet, valveless conduits for connecting each pump cylinder with a power cylinder independent of said valve, conduits respectively connecting the valve with said first-mentioned conduits whereby air is admitted to the latter and the rotary valve, and a member concentric with said valve and co-operating therewith for varying the time of cut-off to correspondingly vary the volume admitted to said pump cylinder.

4. In a multi-cylinder explosion engine, the combination with a plurality of power cylinders each having an unalined pump cylinder, of valveless conduits connecting each pump cylinder with an unalined power cylinder, a hollow rotary valve for controlling the admission to each of said pump cylinders and having an open end induction port, and an adjustable sleeve for varying

the time of cut-off of said valve correspondingly to each of the pump cylinders.

5. In a multi-cylinder explosion engine, the combination with a plurality of power cylinders each having an alined pump cylinder, of a hollow rotary valve controlling the admission to each of said pump cylinders, the chamber within said valve constituting a manifold having an induction passage at the end of the valve, valveless conduits connecting each pump cylinder with an unalined power cylinder, means for introducing a measured quantity of liquid fuel into the path of the air passing through each of said conduits, a rotary cut-off cooperating with said valve, and means for proportionately varying the liquid fuel feed to variations in said cut-off.

6. In a multi-cylinder explosion engine, the combination with a plurality of cylinders and a pump corresponding to each cylinder, of conduits connecting each pump to its corresponding cylinder, a valve for controlling the admission of air to the pumps, an adjustable member co-operating with said valve for varying the time of cut-off and a common means for adjusting said member and varying the liquid fuel supply to said engine.

In testimony whereof I affix my signature in presence of two witnesses.

ERNEST R. FRIED.
